UNITED STATES PATENT OFFICE.

JOHN B. DE MATTEIS, OF NEW YORK, N. Y., ASSIGNOR OF ONE-HALF TO SAMUEL WIRA, OF NEW YORK, N. Y.

SAFETY-ENVELOP.

1,104,169.

Specification of Letters Patent. Patented July 21, 1914.

Application filed October 1, 1912. Serial No. 723,354.

To all whom it may concern:

Be it known that I, JOHN B. DE MATTEIS, a citizen of the United States, and resident of the borough of Manhattan, in the city and State of New York, have invented a new and useful Improvement in Safety-Envelops, of which the following is a specification.

The object of my invention is to provide a novel form of safety envelop with the parts so constructed and arranged that it will be impossible for the contents of the envelop to be removed without so mutilating the envelop as to make it obvious that the envelop had been tampered with.

A practical embodiment of the invention is represented in the accompanying drawings in which,

Figure 1 is a view looking toward the back of the envelop, with the parts partly closed, portions being broken away to more clearly illustrate the parts beneath the same. Fig. 2 is a front view of the envelop with the parts in the position shown in Fig. 1. Fig. 3 is a face view of the envelop, showing the manner of finally sealing by the postage-stamp. Fig. 4 is a section in the plane of the line A—A of Fig. 3. Fig. 5 is a section in the plane of the line B—B of Fig. 3, and Fig. 6 is an inside view of the envelop with the parts unfolded.

The envelop comprises a main rectangular portion 1, and folding flaps 2, 3, 4 and 5. The flap 5 has an inclined tongue 6, of considerable length, projecting therefrom, for use in interlocking the flaps 2, 3 and 4 together and securing them to the main portion 1, as follows: The flap 2 is provided with a tongue receiving slit 7, the flap 3 with a tongue receiving slit 8, and the flap 4 with a tongue receiving slit 9. These slits 7, 8 and 9 register when the flaps 2, 3 and 4 are folded. The main portion 1 has a tongue receiving slit 10 therethrough, in its corner where the stamp 11 is placed.

In sealing the envelop, the flaps 2, 3 and 4,

are folded over the letter or other contents, not shown herein. The tongue 6 is then inserted from the exterior through the slits 7, 8 and 9, for interlocking the flaps and 50 then outwardly through the slit 10. The stamp 11 is then applied in such a position that it overlaps the projecting end of the tongue 6, and thus secures the flaps to the main portion 1. The superfluous projecting 55 end of the flap 6, may then be removed, as shown in Fig. 3.

As a further protection for preventing the removal of the stamp and thus permit the withdrawal of the tongue 6, as for instance, by steaming the stamp, I provide the inner face of the main portion 1, with a coating 12 of wax or other material which will discolor the exterior of the envelop, should any attempt be made to remove the 65 stamp 11 by heat. As a still further protection, the flaps 2, 3, 4 and 5 may be provided with gummed edges 13, 14, 15, 16, 17.

What I claim is:

A safety envelop comprising a main portion having an inclined slit in one of its corners, two side flaps and one end flap having inclined slits arranged to be brought into parallelism with one another when the flaps are folded and the other end flap having an inclined tongue arranged to be passed inwardly through the slits in the two side and other end flaps at right angles thereto for locking the flaps together and thence outwardly through the inclined slit 75 in the corner of the main portion, the protruding end of the tongue being adapted to be secured by a stamp to prevent the withdrawal of the tongue.

In testimony that I claim the foregoing as 85 my invention, I have signed my name in presence of two witnesses, this thirtieth day of September 1912.

JOHN B. DE MATTEIS.
